UNITED STATES PATENT OFFICE.

BERNHARD COLUMBUS, OF NEW YORK, N. Y.

GAS-BURNER.

SPECIFICATION forming part of Letters Patent No. 733,160, dated July 7, 1903.

Application filed June 18, 1902. Serial No. 112,205. (No model.)

To all whom it may concern:

Be it known that I, BERNHARD COLUMBUS, a citizen of the United States, and a resident of the city of New York, borough of Manhattan, in the county and State of New York, have invented new and useful Improvements in Gas-Burners, of which the following is a full, clear, and exact description.

The invention relates to incandescent gas-burners of the Bunsen type; and the object of the invention is to provide a new and improved gas-burner which is simple and durable in construction and arranged to insure a perfect mixture of the air and gas, to allow of regulating the amount of gas to the minutest degree, and to permit of maintaining a pilot-flame of a mixture of air and gas whenever the valve-plug is turned into a closed position.

20 The invention consists of novel features and parts and combinations of the same, as will be more fully described hereinafter and then pointed out in the claim.

25 A practical embodiment of the invention is represented in the accompanying drawings, forming a part of this specification, in which similar characters of reference indicate corresponding parts in all the views.

30 Figure 1 is a sectional side elevation of the improvement. Fig. 2 is an enlarged sectional side elevation of the mixing-chamber and gas-supply. Fig. 3 is a transverse section of the same on the line 3-3 of Fig. 2, showing the valve-plug in an open position. Fig. 4 is a like view of the same, showing the valve-plug in a closed position; and Fig. 5 is a perspective view of the valve-plug.

35 The valve-body A of the gas-burner is connected at one end with the gas-supply pipe B and carries at its other end an integral nozzle C, discharging the gas in a fine jet into a preliminary mixing-chamber D, having air-inlets D', surrounding the nozzle C. The lower end of the mixing-chamber D screws 40 on the body A, and on the said chamber D, near the upper end thereof, is formed an external collar D², on which rests the lower end of the shank E' of an enlarged final mixing and heating chamber E, provided in its top 45 with a screen E², opening into a mantle E³, hung at its upper end on a supporting-rod E⁴, vertically movable in a socket E⁵ and adapt-

ed to be secured therein by a set-screw E⁶. The socket E⁵ is attached to the inside of a holder E⁷, attached to the shank E', and serves 55 to hold a chimney or globe E⁸. A spreading-button E⁹ is secured in the center of the screen E² to distribute the mixture of gas and air equally to the meshes of the screen.

The plug F in the valve-body A is provided 60 with a diametrical aperture F' and with a peripheral feed-groove F², intersecting the ends of the aperture F', as plainly illustrated in the drawings. The plug F is provided with a suitable handle F³, adapted to be turned by 65 the operator to turn the plug into an open, gradually-open, or closed position. When the plug is in a full-open position, (see Figs. 2 and 3,) then the gas under pressure from the supply-pipe B passes in a jet out of 70 the nozzle into the preliminary mixing-chamber D, and thus draws air into the inlets D', and this air mixes with the gas in the said chamber and finally passes into the final mixing-chamber and through the screen E² 75 to burn on the top thereof within the mantle E³ to render the latter incandescent.

The middle portion of the preliminary mixing-chamber D is made in the shape of two frustums of cones united at their apex ends, 80 so that the air and gas are first compressed and then allowed to expand to insure an intimate mixture of the air and gas. By reference to the drawings it will be seen that the side of the nozzle C is tapering, and the 85 nozzle extends about the height of the inlets D' to insure a full flow or rush of air into the chamber D when the jet of gas issues from the nozzle.

When the valve-plug F is turned into a 90 closed position by the operator manipulating the handle F³ correspondingly, (see Fig. 4,) then gas can pass from the supply-pipe B through the groove F² to the nozzle C, and this gas forms a mixture with the air entering the inlets D', so that a pilot-flame remains burning in the mantle above the screen E² at the time the plug F is in a closed position.

It is understood that the peripheral groove 100 F² is comparatively small, so that only a very small quantity of gas can pass from the supply-pipe B to the nozzle C at the time the plug F is in a closed position, as shown in Fig. 3.

Having thus described my invention, I claim as new and desire to secure by Letters Patent—

An incandescent lamp-burner, comprising 5 a valve-body having a plug and an integral nozzle; a preliminary mixing-chamber removably secured on the valve-body and having its middle portions formed of two frustums of a cone united at their apex ends; said 10 preliminary mixing-chamber having vertical air-inlets at its lower end opposite said nozzle, said inlets extending upwardly even with the top of the nozzle; the upper portion of said preliminary chamber having an external collar at the termination of its conical portion; a final mixing and heating chamber having an enlarged upper portion and a lower portion adapted to telescope snugly over the upper section of the primary mixing-chamber and rest upon the external collar thereof, 15 the middle portion of said final mixing-cham-

ber being gradually reduced or tapered from the enlarged portion to merge into the parallel walls forming the lower portion; the top of said primary mixing-chamber terminating 25 in the lower portion of said final mixing-chamber below the lower end of the tapered section; a chimney and mantle support carried upon the lower end of said final mixing and heating chamber and a screen on top of 30 said chamber; and a conical button in the center of said screen with its lower end extending downwardly into the chamber, as specified and for the purpose set forth.

In testimony whereof I have signed my 35 name to this specification in the presence of two subscribing witnesses.

BERNHARD COLUMBUS.
